(57) **CLAIM**

The ornamental design for a tricycle body, as shown and described.

DESCRIPTION

FIG. 1 is a perspective view of the tricycle body.

FIG. 2 is a front elevation view of the tricycle body, shown without the fenders for ease of illustration.

FIG. 3 is a left side elevation view of the tricycle body.

FIG. 4 is a top plan view of the tricycle body.

FIG. 5 is a rear elevation view of the tricycle body; and,

FIG. 6 is a left side elevation view of the tricycle body. The broken lines showing the remainder of a tricycle form no part of the claimed design.
